RAIL ANCHOR

Harold G. Warr, Park Ridge, Ill., assignor to
 Poor & Company, Chicago, Ill., a corporation
 of Delaware

Application December 27, 1938, Serial No. 247,902

23 Claims. (CL 238—327)

This invention relates to a rail anchoring device of the general type which includes a jaw portion adapted to overlie and grip the top surface of the base portion of a rail and a portion adapted to abut against a side face of the rail supporting structure so as to resist longitudinal movements of the rail.

The above general type of anchor device heretofore made has ordinarily been formed from a metal bar by bending the bar into hook form to provide one or more jaws which overlie the top surface of the rail base so as to grip the rail base at a location where the rail is unsupported by an adjacent cross-tie or tie plate. In other words, the under rail portion of such type of anchor device is located at one side of an adjacent cross-tie so as to bear against a side face thereof and the jaw or jaws of the device engage the top surface of the rail base within, or substantially within the side planes of the said under rail portion of the anchor.

The above jaw construction as heretofore made presents certain distinct advantages over other proposed forms in that it has only one bend and, therefore, simplifies the manufacture of the device. It also makes it practicable to accurately form the anchor device with rail gripping surfaces of such width as will exert the most effective grip on the top and bottom surfaces of the rail when the under-rail portion of the anchor device is pressed against the side face of the cross-tie in a manner to produce a canting grip on the top and bottom surfaces of the rail base flange.

A principal object of the invention is to provide, in a rail anchor device of the above general class, certain improved constructions which increase the efficiency of the anchor as a whole and which will be highly effective in protecting the base flange of the railroad rail from being notched or otherwise seriously damaged when the rail anchor jaw overlying the rail base flange is struck by a derailed wheel or by dragging rigging of a car.

A more specific object is to provide a rail anchor of simplified construction in which a jaw portion adapted to overlie the base flange of the rail is formed with a single hook shaped bend and which also includes novel means for rigidifying the jaw and for shielding the rail base flange from the shearing strains such as those ordinarily imposed thereon when a derailed wheel or dragging rigging of a car strikes the upper jaw portion of the usual form of anchor device now in general use. In this connection the in-

vention contemplates, as one specific construction, provision of a jaw having a relatively high rigidifying fin which is adapted to be bent or crushed when struck squarely on the top or side and which is also formed with oppositely inclined edges which converge to form a sharp peak disposed at one side of the rail head, whereby a derailed wheel or other object striking the inclined outer edge of the fin will be deflected clear of the rail flange and whereby an object striking the inclined inner edge of the fin will be deflected inwardly against the side face of the rail head, thereby producing a swaging or lateral force sufficient to dislodge the anchor from the rail without damaging the rail base.

Another object is to provide a rail anchor device with certain other novel and improved constructions which give the device a tie bearing face of large area and which also include means of appropriate widths adapted to overlie the top face of the cross-tie so as to abut against an edge face of a tie plate; the said tie plate abutment means being so formed as to avoid increasing the width of the overlying jaw or offsetting the under surface thereof to restrict its rail gripping surface to the desired width.

A further object is to provide a novel and improved method of forming an anchor device from a rolled metal bar of angular configuration in cross section and including a relatively wide and thin reinforcing web or flange, whereby the said bar may be bent into hook form to provide an upper jaw having an accurately formed rail gripping surface of predetermined width and whereby the said rigidifying web or flange above the upper jaw is so stretched by the tension therein during the bending operation as to form an upstanding fin having a height substantially equal to the original width of the said web and having oppositely inclined edges which converge into a peak which, when the anchor is in its applied position on a rail, assumes a position at a substantial distance laterally from the side plane of the rail head.

Other objects and advantages of the invention will be readily apparent from the detailed description of the construction and operation of the embodiments illustrated in the accompanying drawings, wherein:

Fig. 1 is a cross-sectional view of a railroad rail showing a rail anchor device constructed in accordance with this invention applied to the base flange of the rail in a position to abut against the cross-tie and tie plate of the rail supporting structure and illustrating also two of

the many possible conditions which may exist when the overlying jaw of the anchor is struck by a derailed wheel.

Fig. 2 is a section taken lengthwise of the rail on line 2-2 of Fig. 1, looking in the direction indicated by the arrow.

Fig. 3 is a plan view of the structure shown in Fig. 1, the head portion of the rail being broken away.

Fig. 4 is a view in perspective of the rail anchor device shown in the preceding figures.

Fig. 5 is a plan view of a metal blank from which the anchor device shown in the preceding figure is formed.

Fig. 6 is a cross-sectional view through the blank taken on line 6-6 of Fig. 5.

Fig. 7 is a fragmentary view of the die members employed to form the anchor device and illustrates also the blank shown in Fig. 5 bent around the forming die.

Fig. 8 is a cross-sectional view on line 8-8 of Fig. 7 illustrating the manner in which the bending pressure is applied to the lateral flanges of the bar at opposite sides of the rigidifying web.

Fig. 9 is a view similar to Fig. 1, but illustrates a slightly modified embodiment.

Fig. 10 is a cross-sectional view taken on line 10-10 of Fig. 9.

Fig. 10a is a similar sectional view showing an anchor made from an L-shaped bar of different cross-section.

Fig. 11 is a plan view showing the device of Fig. 10 applied to the base flange of a rail.

Fig. 12 is a view similar to Fig. 8, but illustrating the die members of appropriate form for use in connection with the manufacture of the modified anchor device shown in Figs. 9, 10 and 11 and

Fig. 13 is a fragmentary plan view of the lower die member showing a special construction for imparting an inclined face to the locking shoulder portion of the anchor.

Referring first to Figs. 1 to 8, inclusive, of the drawings: 10 designates a railroad rail of the well known form in which the base flanges 11-12 project beyond the side planes of the rail head 13. The rail is supported on a supporting structure comprising an ordinary wooden cross-tie 14 and a tie plate 15 interposed between the base portion of the rail and the top surface of the cross-tie. The tie plate may be secured to the cross-tie in any suitable manner, for example, by means of cut spikes 16-16 which serve the two-fold purpose of securing the plate 15 to the cross-tie and retaining the rail 10 on the plate. The said tie plate is positioned on the cross-tie in spaced relation to the side faces of the tie substantially as shown in Figs. 2 and 3. This arrangement, therefore, provides a space 17 between the bottom of the rail base and the top surface of the cross-tie.

The specific form of rail anchor device shown in said Figs. 1 to 8, inclusive, is made from a rolled metal bar angular in cross section. Preferably, the said bar is substantially T-shaped in cross-section so as to provide laterally extending arms 18 and 19, either of which is adapted to overlie the top surface of the cross-tie 11 so as to bear against an edge surface 20 of a tie plate 15, and providing a wide thin flange or web 21. Preferably the web is located at one side of the longitudinal center of the bar so that the lateral arm 18 will be somewhat wider than the arm 19. The arm 18, however, is preferably recessed at 18a during the rolling of the bar so that the rail

gripping surface 18b thereof will be of uniform width throughout the length of the bar. The body portion of the anchor device including the major portion of the bar extends horizontally across beneath the rail base in a position to abut against the side face of a cross-tie and against the said edge surface 20 of the tie plate, as shown in Fig. 2. The bar is bent at one end into hook form to provide upper and lower jaws 22 and 23 which are adapted to be driven into spring clamping engagement with the top and bottom surfaces of the rail base flange 11. An up-pressed shoulder 24 formed at the other end of the bar provides a locking means which engages over the lower corner portion of the rail base flange 12 so as to hold the anchor device on the rail.

The said hook portion of the anchor device is preferably formed to provide a substantial clearance 25 between the edge of the rail base flange 11 and the curved inner surface of the hook shaped bend. There is also preferably a clearance space 26 between the top surface of the base flange 11 and the under surface of the jaw 22 so that said jaw will grip the flange only at the surface 27 near the inner end of the jaw. The depending web 21 of the bar extends around the hook portion of the anchor device so as to provide the desired strength to the upper jaw 22. The end portion of the said web is formed to provide a relatively sharp peak portion 28 which, when the anchor is in its applied position, assumes a position at a substantial distance laterally from the side plane of the rail head. The end 29 and longitudinal edge 30 of the said web 30 extend downwardly from the said peak 28 at substantially equal angles so as to provide inner and outer deflecting surfaces adapted when struck by a derailed wheel or other object to deflect the object outwardly from the rail base flange and/or force the anchor off the rail and thereby prevent such impact against the overlying jaw of the anchor from punching the anchor jaw through the base flange of the rail or otherwise seriously damaging the rail base flange. In order to illustrate the manner in which the deflecting surfaces 29 and 30 function to prevent notching of the rail flange when the jaw 22 is struck by a derailed wheel, two derailed wheels designated 31 and 32 are shown in outline in Fig. 1. When a derailed wheel, for example, wheel 31 moves along the rail in the manner indicated, the flange of the wheel striking the deflecting surfaces 29 will bend the jaw downwardly to the extent permitted by the clearance space 26. This downward bending of the upper jaw relieves the gripping action of the lower jaw 23 on the bottom surface of the rail base and also releases the locking shoulder 24. Simultaneously with the above distortion which relieves the grip of the anchor on the rail, the downward force of the wheel flange on the inclined deflecting surface 29 forces the jaw 22 off the rail base flange. In the event that the flange or other portion of a derailed wheel, for example, wheel 32 strikes the anchor jaw at a location beyond the peak 28 of the web, the downward force of the impact is received by the deflecting surface 30 so as to deflect the wheel outwardly from the rail. The force of the impact on the said deflecting surface 30 also distorts the jaw 22 by bending it downwardly in the manner previously described and forces it inwardly upon the rail base flange 11, thereby spreading the hook portion of the anchor so that the said jaw 22 thereof is either broken or dislodged from the rail flange. In the event that a derailed wheel

or other object strikes the peak 28 of the reinforcing web, the relatively small amount of metal at this point is readily crushed or bent, and the entire web above the jaw is usually broken off along the line A—A of Fig. 2, thereby cushioning the force of the impact and/or resulting in dislodgment of the anchor from the rail before the lowest portion of the wheel passes over the anchor jaw.

The above rail flange protecting feature of the invention may obviously be obtained when the anchor device is formed from bars other than of T-shaped configuration. However, the T-shaped bar herein shown has certain other advantages, for example, depending flange 21 provides a centrally arranged reinforcement which imparts equal resistances to opposite edge portions of the anchor jaws and the lateral arms 18 and 19 may be suitably proportioned to accommodate different spacings between the tie plate and the side faces of cross-ties.

In constructions in which the arm 18 of the bar is substantially greater than the arm 19, portions of the arm 18 are cut away along the line of the offset or recess 18a, as indicated at 33 and 34 (Fig. 5) so that the tie plate abutting portion 35 projects laterally from the other edge portions of the body. The said portion 35 being offset downwardly, as previously described, does not affect the width of the anchor for exerting a canting grip on the top and bottom surfaces of the rail base, for example, when the body portion of the anchor is pressed against the cross-tie, regardless of which side of the anchor is engaged with the cross-tie. By cutting away the said portion 34, the locking shoulder 24 is made of the same width as the bearing 27 of the jaw 22 and therefore provides a more effective shackle gripping action on the vertical edge portion of the rail base when the anchor is subjected to forces tending to turn it about a vertical axis. Furthermore, the offset tie plate abutment 35 does not project beyond the side edges of the rail base. Therefore, water and other corrosion producing matter will not readily collect in the recess 18a.

When forming the anchor herein shown the bar shown in Fig. 5 after the portions 33 and 34 have been cut away, is pressed between the die members 38 and 39; the upper die member being recessed, as indicated at 40, to receive the web 21 of the bar. This pressing operation forms the offset locking shoulder 24, the latter being formed by pressure applied to the lateral arms 18 and 19 at opposite sides of the web 21. The other end of the bar is then bent around the portion 41 of the die 39 so as to form the hook shaped portion of the anchor. This bending operation is performed by a wing arm 42, which is guided in its movement by a curved surface 43 on the die 39. The said wing arm is preferably recessed to provide portions 45—46 which stand on opposite sides of the web 21 of the bar. Preferably, the bending pressure is applied to the lateral arms 18—19 relatively close to the juncture of the web 21 with the lateral arms of the bar so that the metal at the end of the jaw 22 and lying within the sides planes of the web 21 will be forced upwardly against the under surface 47 of the die 39 and thereby avoid any substantial depression being formed in the rail engaging surface 27 of the anchor jaw 22. By applying the bending pressure to the lateral arms of the bar in the above manner, the web 21, being free of pressure on its outer edge is stretched both lengthwise and vertically of said jaw 22.

The lengthwise stretching action positions the peak 28 of the web outwardly from the end of the said jaw to form the inclined edges 29 and 30 and the vertical stretching of the web maintains the said peak 28 at a height which is substantially equal or slightly greater than the original width of the web. The said web is maintained in a position perpendicular to the lateral arms of the bar during the bending operation by the position of the members 45—46 of the wing arm on opposite sides of the web. The slight thinning of the web 21 at its junction with the arms 18—19, because of the pressure of the wing arm and because of the vertical stretching of the metal in the web does not affect the rigidifying function of the web. This condition, however, increases the tendency of the said web to break, in the manner previously described, along the lines A—A when the web above the jaw 22 is struck sidewise. When the said web is broken in the above manner, the jaw 22 is materially weakened so that, in fact, it may be knocked off the rail by the wheel before the lower portion of the wheel passes over the jaw.

Referring now to the modified anchor shown in Figs. 9, 10 and 11 and to the die members, as shown in Figs. 12 and 13: The modified anchor designated generally by the reference numeral 50 is made from a bar which is preferably substantially L-shaped in cross-section so as to provide a horizontal rail gripping portion 51 and a relatively wide depending flange or web 52 along one edge thereof for bearing against the vertical side face of a cross-tie 14a. The other edge of the said rail gripping portion of the bar is formed with a relatively low but thick reinforcement 53 and the depressed intervening portion 54 is preferably curved. The bar is bent at one end to provide upper and lower jaws 55 and 56 which are spaced from the edge of the rail and grip the top and bottom surfaces of the rail base flange 11a. The hook shaped configuration of the bar is substantially the same as that shown in the previous embodiment so as to provide corresponding clearances 25a—26a between the edge and upper surface of the base flange and the adjacent surfaces of the anchor. The web portion 52 of the bar, which extends above the upper jaw 55, assumes the same shape and position as the corresponding web of the previous embodiment so as to provide a peak portion 28a which is disposed at a substantial distance laterally of the side plane of the rail head and to provide also the downwardly inclined deflecting surfaces 29a—30a which function in the same manner as the corresponding surfaces 29—30 of the previous embodiment.

The rolled metal L-shaped bar is preferably formed with a recess 57 along the edge of the bar adjacent the web 52 so as to limit the rail bearing surface 58 to the exact width desired. This rail gripping surface extends the full width of the bar so that the rail gripping surfaces of the upper and lower jaws will be of equal width. A principal advantage of providing the bar with the recess 57 is that the bending pressure applied to the horizontal portion of the jaw 55 in forming the hook shaped configuration can be applied to the horizontal portion of the upper jaw 50 for the full width of the rail bearing surface 27a and thereby insure the formation of a rail gripping surface of the desired width and at the same time permit the vertically disposed flange 52 to be free of pressure on its outer edge so that it will stretch both vertically and lengthwise of the jaw

55 in the manner previously described so as to maintain the height of the peak 28a at approximately the original width of the web 52. This stretching action of the web may result in displacing the metal at the edge of the recess 57, for example, from the dotted line position, as shown in Fig. 10, to approximately the full line position. The amount of this displacement of metal will vary somewhat in accordance with the temperature of the bar during the bending operation. However, in the constructions shown, such distortion will be confined substantially to the metal beyond the contacting surface of the wing arm. The said wing arm 42a is formed with a recess to receive the depending flange 52 of the bar during the bending of the same around the portion 41a of the die 39a. All of the die members correspond substantially to the die constructions shown in Figs. 7 and 8 except that the dies are formed with a contour adapted to fit into the depression 54 formed in the outer face of the horizontal portion 51 of the bar. This interfitting of the wing arm 42a in the said depression 54 insures that the said wing arm will be held in close relation to the fillet of the web 52 and thereby avoid extending the variable distortion 58 beyond the shoulder 59 of the recess 57 formed in the bar. Also the raised portion or shoulder 59 on the die member 41a provides a support bearing for the recessed portion of the bar and therefore prevents the rib 52 from bending toward the left of Fig. 12 during the bending of the bar into hook form. The end of the anchor device, for engaging the other edge of the rail base, is provided with up-pressed shoulders 24a, the rail engaging surface of which corresponds in width to the width of the surface 21a of the jaw 55. This condition is maintained, preferably, by pressing the shoulder portion 24a over the upper edge of the die 39a, the latter of which is provided with an inclined face 60, as shown in Fig. 13, which insures the formation of a suitable clearance 61 between the inner face of that portion of the jaw 24a overlying the depending flange 52. During the offsetting operation of the said shoulder 24a the material within in the side planes of the web 52 will be drawn, to some extent, downwardly with the other portion of the offset metal and will receive the angular face 63, as indicated in Fig. 11. By forming the said locking shoulder 24a in the above manner, the width of the rail bearing face thereof can be maintained at any desired dimension which will be satisfactory and most effective for cooperating with the width of the surface 21a for exerting a shackle gripping action on the rail transversely thereof when the anchor is subjected to a turning action about a vertical axis.

The modification shown in Fig. 10a is the same as the anchor shown in Figs. 9, 10 and 11 except that the bar is formed with a fillet 64 of relatively large radius instead of the depression 54. The said fillet serves to extend the reinforcement of the web 52a to the opposite edge of the bar. When forming this modified anchor the forming dies, for example, the die 38a and the wing arm 42a, are provided with curved faces as shown in dotted lines 65 and 66, respectively, which correspond to the radius of the fillet 64.

Both modified anchors herein shown may be driven to their applied position on a rail by striking the outer edge of the web 52 or 52a, as the case may be, at the bend of the hook or by striking the lateral portion of the bar. The said an-

chors, when in their applied positions will grip the rail in the same manner as the first described embodiment and the relatively sharp peak form of fin positioned above their upper jaws will function in the same manner as previously described to deflect articles striking the upper jaws thereof and thereby prevents injury to the rail base flange.

While the various features of the invention have been illustrated in connection with two specific embodiments of the invention, it will be obvious to persons familiar with this art that the features of the invention might be embodied in rail anchors of various types and constructions. It will be understood, therefore, that the invention contemplates all such changes in structures and form which come within the scope of the appended claims.

I claim:

1. A rail anchor comprising a bar bent at one end into hook form to provide upper and lower jaws for gripping the top and bottom surfaces, respectively, of the base portion of a railroad rail, said bar having a horizontally disposed portion for engagement with the rail and a relatively wide but thin vertically disposed flange for abutting against a side face of a rail supporting structure and for reinforcing the said upper and lower jaws; the portion of said flange overlying the upper jaw being formed with oppositely inclined deflecting surfaces which incline downwardly transversely of the rail from a peak located outwardly from the rail head a distance sufficient to permit a portion of a derailed car wheel to strike either of said deflecting surfaces.

30 2. A rail anchor comprising a bar bent at one end into hook form to provide upper and lower jaws for gripping the top and bottom surfaces, respectively, of a railroad rail base flange, said bar having a horizontally disposed rail engaging portion adapted to extend over the top surface of a cross-tie for abutting engagement with a tie plate positioned on said cross-tie and having also a relatively wide but thin vertically disposed

40 flange for abutting against a side face of said cross-tie and for reinforcing said upper and lower jaws; the portion of said flange overlying the upper jaw being formed with oppositely inclined deflecting surfaces which incline downwardly transversely of the rail from a peak located outwardly from the rail head a distance sufficient to permit a portion of a derailed car wheel to strike either of said deflecting surfaces.

45 3. A rail anchor comprising a bar having a body portion adapted to extend across beneath a railroad rail, a hook at one end of the body providing a rail gripping jaw which overlies one flange of the rail base within the side planes of

50 said body and grips the top surface of said flange only at a location spaced inwardly from the edge of said flange, and means at the other end of the body for engaging the other flange of the rail base; the said bar being of angular configuration in cross-section to provide a horizontally disposed arm adapted to overlie the top surface of a cross-tie and abut against the tie plate positioned on the cross-tie and including also a vertically disposed flange for bearing against the side face of the cross-tie, the said vertically dis-

60 posed flange extending around said hook and formed with a relatively straight edge which inclines downwardly and inwardly transversely of the rail from a peak located outwardly from the rail head a distance sufficient to permit a por-

tion of a derailed car wheel to strike the said deflecting surface.

4. A rail anchor comprising a bar having a body portion adapted to extend across beneath a railroad rail, a hook at one end of the body providing a rail gripping jaw which overlies one flange of the rail base within the side planes of said body and grips the top surface of said flange at a location beneath the head of the rail, and means at the other end of the body for engaging the other flange of the rail base; the said body being T-shaped in cross section to provide two horizontally disposed arms either of which is adapted to overlie the top surface of a cross-tie and abut against the side face of a tie plate supported on the cross-tie, and a vertically disposed flange for bearing against a side face of the cross-tie, the said vertically disposed flange extending around the said hook and formed with relatively steep deflecting surfaces which incline downwardly in opposite directions transversely of the rail from a peak spaced a substantial distance outwardly from the rail head.

5. A rail anchor comprising a bar having a body portion adapted to extend across beneath a railroad rail, a hook at one end of the body providing a rail gripping jaw which overlies one flange of the rail base within the side planes of said body, and means at the other end of the body for engaging the other flange on the rail base; the said bar being T-shaped in cross section to provide two horizontally disposed arms, either of which is adapted to overlie the top surface of a cross-tie and abut against a tie plate supported on the cross-tie, and a vertically disposed flange for bearing against the side face of the cross-tie, the said vertically disposed flange extending around the said hook and formed with opposite edge portions which incline downwardly transversely of the rail from a peak located outwardly from the rail head a distance sufficient to permit a portion of a derailed car wheel to strike either of said inclined edge portions.

6. A rail anchor comprising a bar having a body portion adapted to extend across beneath the rail, a hook at one end of the body providing a rail gripping jaw which overlies one flange of the rail, and means at the other end of the body for locking engagement with the other flange of the rail base; the said bar being of T-shaped configuration in cross section having horizontal arms of different widths, either of which is adapted to overlie the top surface of a cross-tie and abut against a tie plate positioned on the tie, a portion of the wider horizontal arm being cut away and another portion thereof being offset downwardly from the top face of the bar, whereby the rail gripping surfaces of the bar are of uniform width throughout the length of the anchor.

7. A rail anchor comprising a bar having a body portion adapted to extend across beneath the rail, a hook at one end of the body providing a rail gripping jaw which overlies one flange of the rail base within the side planes of said body, and means at the other end of the body for engaging the other flange of the rail base; the said bar being of T-shaped configuration in cross-section having horizontal arms of different widths, either of which is adapted to overlie the top surface of a cross-tie and abut against a tie plate positioned on the tie; portions of the wider horizontal arm being cut away at opposite ends of the bar and another portion thereof being offset downwardly from the top face of the bar,

whereby the rail gripping surfaces of the bar are of uniform width throughout the length of the anchor and whereby the width of the said locking means is less than the full width of the anchor device.

8. A rail anchor device comprising a bar of angular cross-section, including a horizontal portion and a vertically disposed flange bent at one end to provide a rail clamping jaw adapted to overlie one base flange of a railroad rail with the said vertical flange projecting upwardly from the jaw and formed at the other end with means for engaging the other base flange of the rail; the said vertically disposed flange being of sufficient width whereby the stretching of the metal therein during the forming of the said bend forms the portion of the flange above said jaw into a triangular configuration having its peak located outwardly from the rail head a distance sufficient to permit a car wheel flange to pass between said peak and the rail head.

9. A rail anchor device comprising a bar T-shaped in cross-section, including a vertically disposed flange and horizontal arms at opposite sides of the flange, bent at one end to provide a rail clamping jaw adapted to overlie one base flange of a railroad rail with the said vertical flange extending upwardly from the jaw and formed at the other end with means for engaging the other base flange of the rail; the said vertically disposed flange being of sufficient width whereby the stretching of the metal therein during the forming of the said bend forms the portion of the flange above said jaw into a triangular configuration having its peak located at a sufficient distance outwardly from the side plane of the rail head to permit a car wheel flange to pass between the peak and the rail head.

10. A rail anchor device comprising a bar of T-shaped cross-section, including a vertically disposed flange and horizontal arms at opposite sides of the flange, bent at one end to provide a rail clamping jaw adapted to overlie one base flange of a railroad rail with the said vertical flange projecting upwardly from the jaw and formed at the other end with up-pressed portions of the horizontal flanges for engaging the other base flange of the rail; the said vertically disposed flange being of sufficient width whereby the stretching of the metal therein during the forming of the said bend reduces the thickness of the vertical flange at its juncture with the horizontal flanges of said jaw and also forms the portion of the flange above said jaw into a triangular configuration having its peak located at a substantial distance outwardly from the side plane of the rail head.

11. A rail anchor comprising a bar bent at one end into hook form to provide a clamping jaw for overlying one base flange of a railroad rail and formed at the other end with an up-pressed shoulder for locking engagement with the other flange of the rail base; said bar having a horizontal portion for receiving the bending pressure during the formation of the hook and having a vertically disposed flange of sufficient width whereby the stretching of the metal therein during the forming of the hook imparts to that portion of the flange above said jaw a triangular configuration having its peak located at a substantial distance outwardly from the side plane of the rail head and reduces the thickness of the vertical flange at its juncture with a horizontal portion of the jaw.

12. A rail anchor comprising a bar bent at one

end into hook form to provide a clamping jaw for overlying one base flange of a railroad rail and formed at the other end with an up-pressed shoulder for locking engagement with the other flange of the rail base; said bar being T-shaped in cross-section to provide a horizontal portion for receiving the bending pressure during the formation of the hook and a vertically disposed flange of sufficient width whereby the stretching of the metal therein during the forming of the hook imparts to that portion of the flange above said jaw a triangular configuration having its peak located at a substantial distance outwardly from the side plane of the rail head and reduces the thickness of the vertical flange at its juncture with a horizontal portion of the jaw.

13. A rail anchor comprising a bar bent at one end into hook form to provide a clamping jaw for overlying one base flange of a railroad rail and formed at the other end with an up-pressed shoulder for locking engagement with the other flange of the rail base; the inner face of said shoulder being offset outwardly for a portion of its length so that the effective length of the shoulder for engaging the rail is less than the full length of the shoulder.

14. A rail anchor comprising a bar bent at one end into hook form to provide a rail clamping jaw for overlying one base flange of the rail and formed at the other end with an up-pressed shoulder for locking engagement with the other flange of the rail base; a portion of said bar underlying the base flange of the rail being offset downwardly so as to reduce its effective width for bearing against the rail and the inner face of said shoulder being offset outwardly adjacent an edge thereof for a portion of its length so that the effective length of the shoulder for engaging the rail is less than the full length of the shoulder.

15. A rail anchor comprising a bar formed at one end with a hook portion to provide upper and lower jaws for gripping the top and bottom surfaces, respectively, of the base portion of a rail, said bar having a horizontally disposed portion for engagement with the base portion of a rail and having a low depending flange along one edge and a relatively wide but thin depending flange along the other edge for reinforcing the upper and lower jaws; the portion of the wide flange overlying the upper jaw being formed with oppositely inclined deflecting surfaces which converge into a peak portion at a substantial distance outwardly from the side plane of the rail head.

16. A method of forming a rail anchor by bending a bar having a horizontally disposed portion and a vertical flange into hook form to provide the anchor with rail gripping upper and lower jaws rigidified by said vertical flange; comprising bending the bar around a suitable form by application of bending pressure exclusively to the horizontal portion of the bar, whereby the vertically disposed flange is free to stretch both vertically and lengthwise of the hook during the bending operation.

17. The method of forming a rail anchor by bending a bar having a horizontally disposed portion and a vertical flange into hook form to provide the anchor with rail gripping upper and lower jaws rigidified by said vertical flange, comprising bending the bar around a suitable form by application of bending pressure exclusively to the horizontal portion of the bar and in close relation to the vertical flange, whereby metal

adjacent the base of the flange is pressed against the form to provide a rail gripping surface of predetermined width and whereby the vertically disposed flange of the bar is free to stretch both vertically and lengthwise of the hook during the bending operation.

18. The method of forming a rail anchor by bending a bar T-shaped in cross section into hook form to provide the anchor device with rail gripping upper and lower jaws rigidified by an outwardly projecting flange; comprising bending the bar around a suitable form by application of bending pressure exclusively to the horizontal portion of the bar at opposite sides of the outwardly projecting flange and in close relation to the juncture of said flange, whereby the metal of the horizontal portion lying within the side planes of the outwardly projecting flange is displaced inwardly toward the form around which the said bar is bent and whereby the outwardly projecting flange is free to stretch both vertically and lengthwise of the hook during the bending operation so that the portion of said flange overlying the upper jaw will form a peak shaped fin having oppositely inclined edges.

19. The method of forming a rail anchor by bending a bar L-shaped in cross-section into hook form to provide the anchor device with rail gripping upper and lower jaws rigidified by the vertically disposed flange of the bar; comprising bending the bar around a die by application of bending pressure exclusively to the horizontal portion of the bar at one side of the vertical flange thereof to form a rail gripping surface of predetermined width which is less than the total width of the bar.

20. A rail anchor device comprising a bar bent into hook form to provide upper and lower jaw portions for gripping the top and bottom surfaces, respectively, of one base flange of a railroad rail, the upper jaw being formed to bear on the top surface of said flange only at a location spaced inwardly from the edge of the flange and is provided on its top face with a deflecting surface which inclines downwardly and inwardly transversely of the rail from a point located outwardly from the rail head a distance sufficient to permit a portion of a derailed car wheel to strike the deflecting surface, and the said deflecting surface being inclined relative to the vertical center of the rail at an angle sufficiently acute to translate the downward force exerted by the wheel into a horizontal component of sufficient force to dislodge the anchor device from the rail.

21. A rail anchor device provided with upper and lower jaw portions for gripping the top and bottom surfaces, respectively, of the base portion of a railroad rail, the said upper jaw being formed with an outwardly projecting fin provided with inner and outer deflecting surfaces which incline downwardly transversely of the rail from a peak located outwardly from the rail head a distance sufficient to permit a portion of a derailed car wheel to strike the inner deflecting surface and the said inner deflecting surface being inclined relative to the vertical center of the rail at an angle sufficiently acute to translate a downward force exerted by the wheel into a horizontal component of sufficient force to dislodge the anchor device from the rail.

22. A rail anchor device provided with upper and lower jaw portions for gripping the top and bottom surfaces, respectively, of the base portion of a railroad rail, the said upper jaw being formed

with a relatively high but thin vertically disposed fin extending transversely of the rail, the opposite edges of which provide inner and outer deflecting surfaces which incline downwardly transversely of the rail from a peak located outwardly from the rail head a distance sufficient to permit a portion of a derailed car wheel to strike either of said deflecting surfaces, and the deflecting surfaces being inclined at angles sufficiently acute relative to a vertical plane passing through said peak to translate the downwardly exerted force of the wheel into a horizontal component of sufficient force to shift the anchor jaw in a direction transversely of the rail.

23. A rail anchor comprising a bar bent at one end into hook form to provide upper and lower jaws for gripping the top and bottom surfaces, respectively, of a railroad rail base flange, said

5 bar having a horizontally disposed body portion for engagement with the rail and a vertically disposed flange which extends around the said hook portion to reinforce the upper and lower jaws, the portion of the vertical flange overlying the upper jaw having inner and outer deflecting surfaces which incline downwardly transversely of the rail from a peak located outwardly from the rail head a distance sufficient to permit a 10 portion of a derailed car wheel to strike either of said deflecting surfaces, and the deflecting surfaces being inclined at angles sufficiently acute relative to a vertical plane passing through said peak to translate the downwardly exerted force of the wheel into a horizontal component of sufficient force to shift the anchor jaw in a direction transversely of the rail.
